DRAFT RIGGING

Byers W. Kadel, Baltimore, Md., assignor to The Symington Company, New York, N. Y., a corporation of Maryland

Application August 28, 1929, Serial No. 389,014

8 Claims. (Cl. 213—69)

This invention relates to draft rigging and, more particularly, to the connection between a coupler, yoke and associated cushioning mechanism in railway draft rigging, whereby relative angling between the parts is permitted.

The principal object of my invention, generally considered, is to provide railway draft rigging involving a coupler, a yoke and associated cushioning mechanism in which provision is made for angling of the coupler by the use of equalizing devices preferably disposed, not only between the coupler and yoke, but between said members and associated cushioning mechanism.

Another object of my invention is to provide, in railway draft rigging involving a key connected coupler and yoke with cushioning mechanism embraced between said yoke and coupler, preferably separate segmental shims at the ends of said cushioning mechanism for respectively engaging the stem of the coupler and the rear end of the yoke to permit relative angling or equalization between the parts.

A further object of my invention is to provide railway draft rigging involving a key connected coupler and yoke operatively associated with cushioning mechanism in which curved equalizing shims are provided, not only to permit angling between the coupler and yoke, but also between the cushioning mechanism and said members.

A still further object of my invention is to provide cushioning mechanism particularly adapted for use with railway draft rigging in which each end of said mechanism is formed with a concavely curved pocket with a convexly curved shim seating therein and interlocked with respect thereto, whereby associated draft rigging is permitted to angle or equalize with respect to said mechanism.

Other objects and advantages of the invention relating to the particular arrangement and construction of the various parts will become apparent as the description proceeds.

Referring to the drawing illustrating my invention, the scope whereof is defined by the appended claims.

Figure 1 is a horizontal sectional view through the center or draft sills of a railway vehicle showing a coupler stem, connected yoke, and associated cushioning mechanism embodying my invention.

Figure 2 is a vertical longitudinal sectional view on the line 2—2 of Figure 1, looking in the direction of the arrows.

Figure 3 is a perspective view of one end of the

cushioning mechanism with the associated segmental shim removed.

Figure 4 is a perspective detailed view of one of the segmental shims for the cushioning mechanism.

Referring to the drawing in detail, like parts being designated by like reference characters, I have shown the stem 1 of a coupler slotted at 2 for receiving a draft key 3 connecting said coupler to a yoke 4 by extending through corresponding slots 5 in said yoke. Although in the present embodiment I illustrate a yoke of the vertical type, I do not wish to be limited to this showing. The coupler and yoke are shown disposed between center or draft sills 6 which are 15 correspondingly slotted at 7, said yoke embracing cushioning mechanism 8, diagrammatically illustrated, which mechanism is received between the sills 6, front draft lugs 9, and rear draft lugs 10 which may be part of the backstop or center 20 filler casting 11. The front draft lugs 9 are preferably slotted to correspond with the sills for receiving the ends of the connecting key 3.

In order to permit angling of the coupler with respect to the yoke and cushioning mechanism 25 to thereby avoid strains when the coupler is subjected to draft or buffing forces, the slot 2 in the coupler stem 1 is preferably enlarged to provide a pocket for receiving the equalizing shim 12 which is notched or formed with webs or flanges 30 13 embracing the key 3 so that it seats thereon, the rear edge of said shim being formed with a convex boss or extension 14 providing a convex bearing surface 15 engaging a correspondingly curved concave bearing surface 16 on the stem 1 35 of the coupler. The slot 2 in the coupler is extended forwardly of the front edge of the key 3 to permit the desired horizontal angling of said coupler without binding between the stem and the key. It will, of course, be understood that 40 a slight amount of vertical angling is also permitted on account of the shim 12 loosely fitting on the key 3 so that the shim may angle or equalize slightly in a vertical direction on said key.

The aforescribed construction merely permits angling between the coupler and yoke resulting in relative swiveling at the bearing surfaces 15 and 16. When such movement takes place, the rear end of the coupler stem engaging the cushioning 50 mechanism 8 would tend to gouge the front face of said mechanism, if the engaging surfaces were plain with no provision for equalizing. It will, of course, be understood that as I have only diagrammatically illustrated the cushioning mech- 55

anism, I am only limited by the scope of the claims and not to whether or not the ends of said mechanism, which are shown broken away, each represent followers or one end a follower and the other a mechanism enclosing casing, or both ends casings enclosing portions of the mechanism and adapted for relative movement toward one another upon compression of the gear. In order to permit free angling of the coupler stem with respect to the front end of the mechanism 8, said front end is formed with a pocket 17 presenting a concave bearing surface 18, preferably curved coaxially with the bearing surface 16 in the coupler stem, when said stem is in engagement with the cushioning mechanism. Fitted in said pocket is a shim 19 preferably corresponding generally in horizontal section with a circular segment, the rear or bearing surface 20 of which is preferably curved to correspond with the bearing surface 18 on the cushioning mechanism. In order to provide for maintaining the shim 19 in place in the pocket 17, said pocket is preferably defined by upper and lower flanges 21 apertured at 22, the lower aperture 22 being for receiving the lower one of the guiding lugs 23 on the shim, with clearance therebetween for the desired relative movement, and formed with inwardly extending guiding lugs 24 for engaging segmental notches 25 in the ends of the shim. The guiding lugs 24 and 23 are so constructed that the shim may be slid in from one side of the pocket 17 behind the lugs 24 until the lower lug 23 drops into position in the lower aperture 22, as shown most clearly in Figure 2, said shim then being interlocked for limited equalizing or angling movement with respect to the cushioning mechanism, as will be understood.

The rear end of the cushioning mechanism is preferably formed with a corresponding pocket 17^a receiving a correspondingly formed shim 19^a interlocked in the same manner with said mechanism. The front face 26 of the rearmost portion of the yoke 4 engages the rear or flat face of the shim 19^a which, when the yoke angles with respect to the cushioning mechanism, results in corresponding swiveling movement of said shim in the cushioning mechanism pocket.

From the foregoing disclosure of my invention, it will be seen that I have provided a coupler, yoke and associated cushioning mechanism connection for permitting limited free angling between the parts in a horizontal plane. Under the influence of draft forces, the rear end of the stem 4 is pulled away from the front end of the cushioning mechanism 8 upon compression of said mechanism, and the angling takes place with movement of the shim 12 in the coupler stem pocket and movement of the shim 19^a in the cushioning mechanism pocket 17^a, if the yoke angles with respect to the cushioning mechanism. Under the influence of buffing forces, however, the rearmost end of the yoke is free to move from the rear end of the cushioning mechanism and the coupler angles with respect to the front end of said mechanism with swiveling between the front shim 19 and the cushioning mechanism, the coupler also swiveling about the shim 12, or the key and shim angling with said coupler as the key is then free from strains, such buffing force being transmitted directly from the coupler stem to the cushioning mechanism which is compressed against the rear lugs 10.

Although I have shown a preferred embodiment of my invention, it is to be understood that the same is merely illustrative and that modifications may be made without departing from my inven-

tion or the spirit and scope of the claims following.

Having now described my invention, I claim:

1. In railway draft rigging, in combination, a coupler, a yoke, means passing through slots in said coupler and yoke for connecting said members, the slot in said coupler being enlarged to form a pocket with a curved bearing surface, a shim fitting said connecting means and received in said pocket, said shim being formed with a correspondingly curved bearing portion engaging the bearing portion on the coupler, cushioning mechanism disposed between the rear ends of said yoke and coupler, and equalizing means loosely disposed between the cushioning mechanism and the stem of the coupler and the rear end of the yoke, respectively, to permit relative angling of said coupler and yoke, the end portions of the cushioning mechanism being provided with shelf portions underlying and supporting said equalizing means, said means being provided with lugs interlocking and loosely received in apertures in said shelf portions.

2. In railway draft rigging, in combination, a coupler formed with a slot in the stem thereof, a yoke associated therewith and formed with registering slots, a key passing through said slots for connecting said coupler and yoke, equalizing means disposed between the rear edge of said key and said coupler for permitting relative angling of said coupler and key, cushioning mechanism embraced by said yoke and disposed rearwardly of the stem of said coupler, the walls of said cushioning mechanism respectively disposed adjacent the rear face of the coupler stem and the rear of said yoke having pockets provided with concave bearing faces, and shims fitting in said pockets and provided with correspondingly curved convex bearing faces engaging the bearing faces in the pockets, the outer faces of said shims being substantially flat and normally engaged by the rear face of the coupler and the front face of the rear portion of the yoke, respectively, said shims being provided with downwardly extending lugs received in apertures in underlying shelf portions on the cushioning mechanism, said cushioning mechanism being provided with lugs lying in front of the upper portions on said shims, whereby said shims are retained in position with respect to the cushioning mechanism while permitted to swivel a limited amount.

3. In railway draft rigging, in combination, a coupler, a yoke, means connecting said coupler and yoke, cushioning mechanism disposed between the rear ends of said coupler and yoke, and equalizing means loosely disposed between the cushioning mechanism and the stem of the coupler to permit relative angling of said coupler, the front end portion of said cushioning mechanism being provided with a shelf underlying and supporting said equalizing means, said means being provided with a lug interlocking and loosely received in an aperture in said shelf.

4. In railway draft rigging, in combination, a coupler, a yoke, connecting means passing through slots in said coupler and yoke, cushioning mechanism disposed between the rear ends of said yoke and coupler, and equalizing means loosely disposed between the cushioning mechanism and the stem of the coupler and the rear end of the yoke, respectively, to permit relative angling of the coupler and yoke, the end portions of the cushioning mechanism being provided with shelves underlying and supporting said equalizing

means, said means being provided with lugs interlockingly and loosely received in apertures in said shelves.

5. In railway draft rigging, in combination, a coupler, a yoke, connecting means passing through slots in said coupler and yoke, the slot in said coupler being enlarged to form a pocket with a curved bearing surface, a shim fitting said connecting means and received in said pocket, said 10 shim being formed with a correspondingly curved bearing portion engaging the bearing portion on the coupler, cushioning mechanism disposed between the rear end of said yoke and coupler, and equalizing means loosely disposed between the 15 cushioning mechanism and the stem of the coupler to permit relative angling of said coupler, the front end portion of the cushioning mechanism being provided with a shelf supporting said equalizing means, said means being provided with a 20 lug interlockingly and loosely received in an aperture in said shelf.

6. In railway draft rigging, in combination, a coupler formed with a slot in the stem thereof, a yoke associated therewith and formed with registering slots, and a connecting key passing through said slots, cushioning mechanism embraced by said yoke and disposed rearwardly of the stem of said coupler, the wall of said cushioning mechanism adjacent the rear face of the 30 stem having a pocket provided with a concave bearing face, a shim fitting in said pocket and provided with a correspondingly curved convex bearing face engaging the bearing face of the pocket, the outer face of said shim being substantially flat and normally engaged by the rear face of said coupler, said shim being provided with a downwardly extending lug received in an aperture in an underlying shelf on the cushioning mechanism, said cushioning mechanism being 35 provided with a positioning lug lying in front of an upper portion of said shim.

7. In railway draft rigging, in combination, a coupler formed with a slot in the stem thereof, a yoke associated therewith and formed with reg-

istering slots, a connecting key passing through said slots, cushioning mechanism embraced by said yoke and disposed rearwardly of the stem of said coupler, the front and rear end walls of said cushioning mechanism having pockets provided with concave bearing faces, and shims fitting in said pockets and provided with correspondingly curved convex bearing faces engaging the bearing faces in the pockets, the outer faces of said shims being substantially flat and normally engaged by the rear face of the coupler and the front face of the rear portion of the yoke, respectively, said shims being each provided with a downwardly extending lug received in an aperture in an underlying shelf portion on the cushioning mechanism, said cushioning mechanism being provided with a lug at each end lying in front of the corresponding portions of said shims for retaining them in position, while permitting a limited amount of movement.

8. In railway draft rigging, in combination, a coupler formed with a slot in the stem thereof, a yoke associated therewith and formed with registering slots, a connecting key passing through said slots, equalizing means disposed between the rear edge of said key and said coupler for permitting relative angling of said coupler and key, cushioning mechanism embraced by said yoke and disposed rearwardly of the stem of said coupler, the front wall of said cushioning mechanism having a pocket provided with a concave bearing face, and a shim fitting in said pocket and provided with a correspondingly curved convex bearing face engaging the bearing face in the pocket, the outer face of said shim being substantially flat and normally engaged by the rear face of the coupler, said shim being provided with a downwardly extending lug received in an aperture in a shelf portion on the cushioning mechanism, said cushioning mechanism having a lug lying in front of the upper portion of said shim for retaining it in place.
